Primary Examiner—Mitchell I Siegel**Attorney, Agent, or Firm—John L. Gray; Kegler, Brown, Hill & Ritter****[57] CLAIM**

The ornamental design for a golf putter head, as shown and described.

DESCRIPTION

FIG. 1 is a perspective view of the design.

FIG. 2 is a side elevation view thereof.

FIG. 3 is a top plan view thereof.

FIG. 4 is an end elevation view thereof.

FIG. 5 is an opposite end elevation view thereof.

FIG. 6 is an opposite side elevation view thereof; and,

FIG. 7 is a bottom plan view thereof.

The broken line showing of a fragmented shaft is for illustrated purposes only and forms no part of the claimed design.
